UNITED STATES PATENT OFFICE.

CARROLL P. WARD, OF MOUNT VERNON, OHIO, ASSIGNOR OF ONE-HALF TO HERMAN HECKLER, OF MOUNT VERNON, OHIO.

GOLF TEE.

Application filed June 30, 1925. Serial No. 40,652.

This invention relates to an improved artificial golf tee and has for its principal object the provision of an inexpensive, efficient and durable tee which is capable of being readily inserted into the ground for use in supporting a golf ball at a proper elevation for driving purposes and which when not in use may be readily carried from place to place by the user for repeated and continued service.

In accordance with the invention there is provided an artificial golf tee consisting of a ball supporting member which comprises a socketed upper surface in which a ball is positioned, said member being provided with a ridge depending stem having a pointed lower extremity to facilitate the insertion of the stem in the ground so as to securely maintain the head of said member in a stable ball receiving position and in combination with this structure I provide a guard or anchor which is connected to said member by an elastic connection, said guard or anchor being provided with a socket in which the shank or stem of said supporting member is adapted to be positioned when the tee is being carried from place to place, the arrangement of parts being such that when the supporting member is inserted in the ground the guard will serve to retain the supporting member in the proximity of the player in the event that the supporting member is struck by the swinging of the club, and when not in use the guard will serve to receive the supporting member, protect and enclose its shank or stud and to enable the same to be carried readily in the pocket of the user without liability of loss or injury to the user.

For a further understanding of the invention reference is to be had to the following description and the accompanying drawings, in which:

Figure 1 is a perspective view showing the improved artificial golf tee comprising the invention in its active position,

Figure 2 is a vertical longitudinal sectional view taken through the tee when the latter occupies an inactive position, and

Figure 3 is a transverse sectional view on the line 3-3 of Figure 2.

Referring more particularly to the drawings the numeral 1 designates my improved golf tee in its entirety. In its preferred form the tee consists of a ball support,

designated generally by the numeral 2, and an anchor or guard 3 which is united with the support by means of a flexible and preferably elastic connection 4.

The support 2 consists in this instance of a circular head 5, ordinarily formed from rubber. The upper surface of this head is concaved as indicated at 6 so as to permit of the positioning of a ball 7 in a secure and positive manner upon the head. Also, positioned within the head 5 and depending rigid therefrom is a wire shank or stem 8, which terminates at its lower end in a pointed extremity 9, adapted to facilitate the manual insertion of the shank into the ground. The upper end of the shank may be provided with an enlarged head 10 which is suitably embedded in the head 5 so as to securely unite the shank with said head. By this arrangement it will be seen that the shank may be forced into the ground until substantially the lower part of the head 5 engages with the ground surface. This anchors the support securely in connection with the ground and permits of the placing of the ball 7 on the concaved surface of the head 5, where the ball will be supported at a suitable elevation above the ground to permit of a free and unobstructed swing of a golf club in the driving of the ball. The support eliminates the use of the natural sand tee and provides a means of a far more convenient nature for holding the ball in a proper position for engagement with a club head.

An important feature in the construction of the support described is the depending rigid metallic shank 8 with its pointed extremity. Prior constructions of this kind have used wood principally in constructing the shank end. Wood, however, has the disadvantage of being rather blunt, is easily broken and furthermore its diameter is such, when strength is secured, to prevent the user from readily inserting the same into the ground. By the use of the wire shank this difficulty is obviated. However, since tees of this kind are used repeatedly it is desirable to provide a means to protect the user from physical injury by the pointed end of the shank. For this reason, and others, I employ the guard 3. In this instance the guard consists of a cylindrical preferably rubber body 11 which has one end thereof provided with a longitudinal and axially extending

socket 13 in which is positioned the shank 8 of the support when the tee is being carried or assumes an inactive position. The other end of the body 11 was formed with an eye 14 to which is connected one end of the elastic band constituting the connection 4, the other end of said connection being joined with an eye 15 provided on the head 5. It will be seen that in use the support is inserted in the ground as previously related, and the guard lies in an idle position on the ground out of the way of the player but connected with the support by means of the elastic band 4. When in this position the anchor serves in a useful capacity, first, after the ball has been hit the player may readily remove the support from the ground by grasping the guard, and since the latter possesses far more body than the head 5 facility is to be had in the removal of the support from the ground, and, second, in the event the club strikes the support, the anchor provides a restraining influence which maintains the tee in the immediate vicinity of the player, where it may be conveniently reached without searching for it. Then, when the tee has been used and it is desired to carry the same to the next place, the shank is removed from the ground and inserted into the socket 13, enabling the tee to be placed in the pocket of the user without any possibility of physical injury. It will be observed that the length of the connection 4 is such that when the support is connected with the anchor the elastic band will be under tension and will exercise sufficient force on the support to securely hold the

shank of the latter free from accidental disengagement with the anchor.

What is claimed is:

1. A golf tee comprising a ball supporting member having a rigid depending shank, a guard having a socket formed therein for the reception of said shank, and an elastic connection between said guard and said supporting member positioned to maintain the shank of said supporting member within said socket.

2. A golf tee comprising a supporting member including a rigid depending stem having a pointed lower extremity to facilitate the insertion of the stem into the ground, a guard having an axial longitudinally extending socket formed therein for the reception of said stem, and a flexible elastic connection between said guard and said supporting member and capable of exercising sufficient pressure to prevent accidental separation of the supporting member from the guard when the stem is positioned within said socket.

3. A golf tee comprising a supporting member including a rigid depending stem, a guard having an axial longitudinally extending socket formed therein for the reception of said stem, and a flexible elastic connection between said guard and said supporting member capable of exercising sufficient pressure to prevent accidental separation of the supporting member from the guard when the stem is positioned within said socket.

In testimony whereof I affix my signature.

CARROLL P. WARD.
